(57) **CLAIM**

The ornamental design for a vehicle wheel cover, as shown and described.

DESCRIPTION

FIG. 1 is a front perspective view of a vehicle wheel cover in accordance with an embodiment of the present invention; and,

FIG. 2 is a front/side perspective view of the vehicle wheel cover of FIG. 1.

The surface ornamentation, logos, written matter and tire are for illustrative purposes only and form no part of the claimed design.
